UNITED STATES PATENT OFFICE.

ROBERT M. KEATING, OF SPRINGFIELD, MASSACHUSETTS.

FLUSHING-VALVE.

1,242,200.

Specification of Letters Patent.

Patented Oct. 9, 1917.

Application filed March 13, 1914. Serial No. 824,449.

To all whom it may concern:

Be it known that I, ROBERT M. KEATING, a citizen of the United States of America, residing at Springfield, in the county of 5 Hampden and State of Massachusetts, have invented a new and useful Flushing-Valve, of which the following is a specification.

My invention relates to improvements in automatic, self-closing, water-closet flushing 10 devices, and is in the nature of an improvement of the valve which forms the subject matter of my application for United States Letters Patent, Serial No. 758,995. This valve in its general structure, as in the other 15 case, consists of a casing having an inlet and an outlet for the water, and being provided with an inlet cage, with main and auxiliary valve members for the control of the intake, and with a retarding piston, and in addition 20 to these parts and members said valve is provided with certain peculiar supporting and operating means for said main and auxiliary valve members, and with certain peculiar means for controlling the escape of 25 the water confined within the retarding chamber of the valve, which chamber is made up in part of said piston, all as hereinafter set forth.

The objects of my invention are, first, to 30 produce a flushing valve that is simple in construction and operation, can be easily and quickly assembled and taken apart, and is capable of producing an after flush in addition to the main flush, either of which may 35 be regulated as to time and amount; second, to provide such a valve with ample means of adjustment to adapt the same to any given condition, and, to afford means whereby the entire interior mechanism of the valve can 40 be most readily removed and replaced without disturbing the casing or the water connections leading thereto and therefrom.

This valve is easily opened by hand for 45 the flushing operation, and automatically closed at the end of such operation, and requires no other cushioning or retarding fluid medium than the water admitted during the flushing operation. A high degree of efficiency is thus obtained simply and without 50 resorting to numerous parts and complicated mechanism.

The after-flush controlling or producing means, in a valve of this type, is of great value, and especially so when obtained as in 55 this case, by cutting down the action of the parts during the closing operation at or near

the end of such operation. The increased retardation of the valve-closing action is produced automatically by decreasing the amount of water permitted to escape under 60 the force of the retarding piston in moving to valve-closing position.

Other objects and advantages will appear in the course of the following description.

A preferred or practical form of embodiment of the invention, whereby I attain the objects and secure the advantages of the same, is illustrated in the accompanying drawings, and I will proceed to describe the invention with reference to said drawings, 70 although it is to be understood that the form, construction, arrangement, etc. of the parts in various aspects are not material and may be modified without departure from the spirit of the invention.

In the drawings, in which like numerals designate like parts throughout the several views, Figure 1 is a central vertical section through a valve, showing the invention as aforesaid, the same being closed; Fig. 2, a similar view, except that here less parts are in section and the valve is shown fully open; Fig. 3, a side elevation of all of the interior structure which is removable upon unscrewing the cap from the outside casing; Fig. 4, 85 a cross-section taken on lines 4—4, in Fig. 1, looking down; Fig. 5, a side elevation of the pusher for the main valve; Fig. 6, a top plan of said pusher, and, Fig. 7, a cross-section on line 7—7, in Fig. 1, looking down. 90

The valve comprises a vertical cylindrical casing which is provided with a cap 2, which cap is screwed into the top of said casing to close the same, and valve mechanism within such casing, which mechanism, including all of its parts and members, is attached to or connected with said cap and removable therewith from the casing, the aforesaid parts and members being so constructed preferably that they with the cap 2 100 form a unit for removal and replacement. This is a very advantageous feature of my invention, because I am thereby enabled to take out such parts and members readily and conveniently whenever necessary for 105 the purpose of removing the main valve seat, repacking, readjusting, or otherwise repairing, replacing, or changing any part of the mechanism needing attention, and as readily and conveniently to restore said 110 parts and members.

The casing 1 has an inlet 3 at the bottom

and an outlet 5 in one side about midway between the two ends of said casing. Pipe connections are made in the usual manner with the inlet end and outlet flange or nozzle 5 of the casing.

On the inside of the casing 1, below the outlet 5, is a flange 6.

As previously observed the cap 2 has a screw connection with the casing 1, this being the preferred construction, and a packing-ring 8 may be introduced between the upper edge of said casing and the overhanging flange of said cap. Depending from the center of the cap 2 is a sleeve 9. Also depending from the cap, but between the center and outer edge thereof, is a tube valve 10. The valve 10 has at its upper end a flange 11 which is directly supported by the cap 2 within a recess provided therein for said flange and normally closed by means of a screw-cap 12. The flange 11 is not tightly confined, but with the valve 10 is left sufficiently loose to enable said valve to tilt to whatever extent may be needed for the proper operation of the parts, as herein-after explained.

Supported on the casing flange 6, with an interposed packing-ring 13, is a regulator for the intake, preferably in the form of an annular cage 14 provided with an adjustable cut-off shutter 15. The cage 14 has a flange 16 at the top, and this is the part that rests on the flange 6. There are vertical slots or ports 17 in the cage 14, and corresponding ports 18 in the shutter 15. A main valve 19 operates in the cage 14 and is guided in its movement by said cage.

The shutter 15 fits under and around the cage 14 to which it is attached by means of a binding screw 20 and a washer 21. Upon loosening the screw 20, the shutter 15 can be rotatably adjusted so as to bring the ports 18 into whatever relationship with the ports 17 may be necessary or desirable in order to admit the required volume of water to the cage 14 and the parts above. After such adjustment the screw 20 is again tightened to prevent displacement of the shutter. It is by means of this shutter that the valve is regulated to different water pressures.

Rising from the flange 16 and in threaded engagement with an upright portion thereof is a member which comprises a main valve-seat, represented at 22, a plurality of uprights 23, and a flange 24 which connects said uprights at the top and is in threaded engagement with the base of the cap 2.

It is now clear that, when the flange 24 is screwed on to the cap 2 and the cage is attached by its flange 16 to the valve-seat 22, these members with their interior mechanism become a unit, so far as their insertion in and removal from the casing 1 is concerned, and that said members after be-

ing removed from said casing can be easily and quickly separated one from another, by the mere act of unscrewing the threaded parts, and as easily and quickly connected again. When the aforesaid members are screwed together and inserted in the casing 1, the cap 2 is screwed down into said casing until the flange 16 is forced tightly against the flange 6 or the packing-ring 13, so that a water-tight joint is formed between said flanges. 70

The valve-seat 22 is provided with a packing-ring 25, which is let into the bottom of said seat and is the part against which the valve 19 actually impinges in closing. The packing-ring 25 is wide enough to extend over onto the top of the cage 17, and so makes a tight joint between said cage and the valve-seat 22. 80

Rising from the valve 19 is a hollow stem 26 which extends upwardly around the sleeve 9. The valve 19 may be screwed on to the base of the stem 26, or otherwise secured thereto, as may be desired. A retarding piston 27 is secured to the stem 26 at or near the upper terminal thereof. This piston fits and operates within the cap 2, and may or may not be provided with a cup-packing, as 28. In the present case the cup-packing 28 is held in place on the piston 27 by means of a disk 29 and a nut 30, the latter being screwed on to the upper end of the stem 26 above said disk. 90

The piston 27 is equipped with a tubular member 31, which member opens at the bottom below said piston, and through one or more lateral ports 32 above said piston. A regulating screw 33 is inserted in the member 31 above the ports 32 for the purpose of increasing or decreasing the size of such ports, accordingly as said screw is turned down or up, so as to govern the amount or volume of water that escapes into said member to pass through the same into the space below the piston 27. The member 31 is so situated that its axis coincides with the axis of the valve 10, and operates up and down in said valve. These parts are so proportioned that, as the piston 27 rises with the member 31, the ports 32 are covered by said valve before said piston reaches the end of its upward stroke. The member 31 has a sliding fit with the valve 10, which is not tight enough to prevent water from being forced between the contacting surfaces. 100 Upon removing the screw-cap 12 access is had through the valve 10 to the screw 33 for the purpose of adjusting the latter. 110

The space within the cap 2 above the piston 27 is the retarding chamber of this valve, the only escape from which, when said piston is making its upward stroke, is by way of the ports 32 and the passage in the member 31 into which said ports open. 120

And the means of escape thus provided be- 130

- comes very much constricted as the piston approaches the end of its up stroke and when the ports 32 pass into the valve 10. Thus the end of the closing operation is 5 rendered slow and time is afforded for the after flush, that is, for a quantity of water to flow through the valve into the bowl so slowly that it remains therein after the real flushing operation has taken place.
- 10 Although the means herein shown and described for cutting down or materially decreasing the flow from the retarding chamber, and which may be termed a progressive retarder, is entirely practicable for the purpose, I do not desire or intend to limit myself to such means, but seek to cover broadly 15 a progressive retarder or any means whereby the escaping fluid which controls the closing of a valve is held back or cut down 20 in volume after having escaped in part.

The valve 19 and the piston 27 are both on the same stem, 26, and so center said stem. Although the stem 26 in part 25 encloses the sleeve 9, there is sufficient space between said stem and around the outside of said sleeve for the passage of water into the retarding chamber which is now designated by the numeral 34.

Slidably mounted in the center of the 30 cap 2 is a plunger 35. The plunger 35 has a shoulder 36 at its inner end which may limit the upward movement of said plunger, and in any event prevents the same from being withdrawn from the top of the cap 2. 35 A knob 37 has its stem tapped into the protruding portion of the plunger 35, and a spindle 38 has its upper terminal tapped into the base of said plunger. The base of the sleeve 9 is closed by means of a screw- 40 plug 39, and a spring 40 is interposed in said sleeve between said plug and the bottom of the plunger 35. The tendency of the spring 40 is to force the plunger 35 with its attached parts upwardly and to retain said 45 plunger and parts in elevated position. The spindle 38 extends downwardly from the plunger 35 through the center of the tube 9, through an opening in the plug 39 and a stuffing-box 41 in said plug, through the 50 lower portion of the stem 26, and finally through the center of the valve 19. Securely fastened to the base of the spindle 38, by means of a nut 42, is an auxiliary or starting valve 43. Let into the upper side of the 55 valve 43 is a packing-ring 44 which is adapted to close a valve-seat 45 in the center of the main valve 19, it being through such seat that the spindle 38 extends. The spindle 38 and the valve 43 must be so adjusted that the packing-ring 44 can be properly seated before the upward movement of the parts is or can be checked by the shoulder 36. When the auxiliary valve is open 60 the passageway is cleared between the cage 14 and the retarding chamber 34, such pas-

sageway consisting of the opening through the valve-seat 45 and the passage through the stem 26.

Screwed onto the spindle 38, or otherwise rigidly attached thereto, directly above the packing-ring 44, is a pusher 46 for the main valve 19. The construction and arrangement of parts are such that, when the auxiliary valve is closed, the head of the pusher 46 stands clear of the main valve, 70 and said head does not come into contact with said main valve until sufficient movement has been given to the spindle 38 to fully open said auxiliary valve.

The operation of the valve is described as 80 follows, it being assumed that all adjustments have been made and the parts stand as shown in the first view. With the hand grasping the knob 37 the operator forces the plunger 35 and spindle 38 downward, 85 against the resiliency of the spring 40 and of the pressure of the water in the lower part of the casing 1 and in the cage 14, until the bottom edge of the rim of the piston 27 comes to rest on top of the uprights 23, 90 when said knob is released, the valve requiring no further attention on the part of the operator. This simple manual act performed by the operator has, however, not only opened the valve and brought about the 95 full flushing operation for which the valve is designed, but started a series of automatic actions which latter do not cease until the after flush has taken place and the valve is again fully closed and all movable 100 parts are in readiness for a repetition of the complete flushing operation, all movements being orderly, quite noiseless so far as mechanical elements are concerned, and certain so that there is no failure to obtain the 105 desired result every time.

When the spindle 38 is pushed down by the knob 37 and the intervening plunger 35, of which latter said spindle really constitutes a part so that the spindle and plunger together might with propriety be classed as one element and termed the plunger of the device, the valve 43 is first carried away from the seat 45, thus breaking the water seal, and a quantity of water immediately 115 rushes through said seat and the stem 26 into the retarding chamber 34. Meanwhile the valve 19 is held to its seat by the water below. Next the pusher 46 encounters the valve 19, but without closing the central 120 opening in said valve, and forces the latter from its seat. As soon as the valve 19 commences to descend, water flows over the same, through the slots 18 and 17, passes through the valve-seat 22 and escapes to the 125 outlet 5. At the end of the down stroke of the plunger the valve is wide open, as shown in Fig. 2.

The size of the retarding chamber 34 increases as the piston 27 descends with the 130

valve 19 and the connecting stem 26, and it is quite possible that some water may enter said chamber through the progressive retarder member 31 which moves down with 5 said piston so as to fully uncover the ports 32. It may be observed here that the valve 10 of the progressive retarder is hung loosely, as hereinbefore noted, so as to accommodate itself to the member 31 as the 10 latter moves up and down in the former.

Having been released by the operator, the plunger 35 begins to rise under the influence of the spring 40. In rising the plunger 35 almost instantly closes the valve 15 43, through the medium of the spindle 38, and the main valve 19, with which said valve 43 is now in contact, is carried upwardly with said valve 43, together with the stem 26, the piston 27, and the progressive 20 retarder member 31. The parts elevated by the members which are elevating the valve 43 under the influence of the spring can rise only as fast as the water in the retarding chamber 34 is expelled by the piston 27 25 through the ports 32 and the passage leading downward from the same in the member 31, no water being able to escape through the valve-seat 45. The slow closing of the valve 19 thus brought about gives ample time for 30 the passage of a sufficient amount of water to flush the bowl. Before the valve 19 is completely closed the ports 32 in the member 31 pass into the valve 10, in consequence of which the flow of the water from the retarding 35 chamber 34 is very materially reduced, such water being able to escape only by being forced upwardly into said tube and around said member until said ports are reached, with the result that the final closing 40 of said valve 19 is extremely slow and allows time and opportunity for a quantity of water to flow into the bowl and to remain therein after the actual flushing operation has taken place. The valve is completely closed when 45 the seating of the main valve takes place and no more water can flow through the valve-seat 45 until the plunger is again forced down.

The single spring in this valve is completely inclosed and protected from the water, as clearly shown in Fig. 1.

Although I have shown and described the members which together constitute what may be termed an interior casing, and which 55 comprise the cage 14, the valve-seat 22 with its uprights 23 and the flange 24, and the cap 2, as being in threaded engagement with each other, it is very apparent that such engagement is not always imperative or even 60 essential. For example, the screw threads may be omitted from the bottom portion of the cap 2 and from the flange 24, without effecting any material change in construction or function, more especially since the 65 interior mechanism would in such an event

hold the members together while being withdrawn from the casing 1.

The packing-ring 25 is to be considered as a part of the seat for the main valve, and the packing-ring 44 is to be considered as a 70 part of the auxiliary or starting valve.

That the progressive retarder absolutely prevents quick action on the part of the main valve at the end of the closing operation, is very apparent, hence it follows that 75 the closing action must be noiseless, and that all liability of water-hammer is removed.

What I claim as my invention, and desire to secure by Letters Patent, is—

1. A flushing valve comprising a casing 80 having an intake and an outlet, a valve-seat in said casing, a valve for said seat, said valve having a valve-seat and being provided with a hollow stem, a retarding piston on said stem, progressive retarding 85 means, for said piston, within said retarding chamber and opening through said piston, a spring-pressed plunger, a valve carried by said plunger for the seat in said first-mentioned valve, and means to unseat said first- 90 mentioned valve after the valve carried by said plunger is unseated.

2: A flushing valve comprising a casing having an inlet and an outlet and provided with a valve-seat, means to close one end of 95 said casing, a retarding chamber at the closed end of said casing, such chamber consisting in part of a piston, a valve for said seat, a hollow stem connecting said valve and piston and opening through both, progressive retarding means for said piston, a tubular member extending from the closed end of the casing into said stem, a plunger extending through said closed end and inwardly through said valve, guide means for 100 said stem at the inner end of said tubular member, a spring in said tubular member to actuate said plunger in one direction, a valve on said plunger for the inlet to said stem, and means to unseat the first valve after the second valve is unseated. 110

3. A flushing valve comprising a casing having an inlet and an outlet and provided with a valve-seat, means to close one end of 115 said casing, a retarding chamber at the closed end of said casing, such chamber consisting in part of a piston, a tubular member extending into said chamber, a member carried by said piston in sliding relation to said tubular member, said second mentioned 120 member opening on both sides of said piston and adapted to have the entrance thereto partially closed by said tubular member as said piston approaches the end of its outward stroke, a valve for said seat, a hollow 125 stem connecting said valve and piston and opening through both, a tubular member extending from the closed end of the casing into said stem, a plunger extending through said closed end and inwardly through said 130

valve, a valve on said plunger for the inlet to said stem, and means to unseat the first valve after the second valve is unseated.

4. In a flushing valve, members including a piston which assists in forming a retarding chamber, a tubular member extending into said chamber, a member carried by said piston in sliding relation to said tubular member inside, said second-mentioned member opening on both sides of said piston and adapted to have the entrance thereto partially closed by said tubular member as said piston approaches the end of its outward stroke, and an adjusting member within said second-mentioned member, for said entrance to said second-mentioned member.

5. In a flushing valve, members including a piston which assists in forming a retarding chamber, a tubular valve member extending into said chamber from one of the walls thereof, such wall having an opening over said member, a screw-cap for said opening, a member carried by said piston in sliding relation to said valve member, said second-mentioned member opening on both sides of said piston and adapted to have the entrance thereto partially closed by said valve member as said piston approaches the end of its outward stroke, and an adjusting member for said entrance to said second-mentioned member, said adjusting member being accessible when said screw-cap is removed.

6. A flushing valve comprising a casing

having an inlet and an outlet and provided with a valve-seat, parts forming a retarding chamber and including a piston, progressive retarding means for said piston within said retarding chamber and opening through said piston, a valve for said seat, a hollow stem connecting said valve and piston, and means to open and close the entrance to said stem.

7. A flushing valve comprising a casing having an inlet and an outlet and provided with a valve-seat, parts forming a retarding chamber and including a piston, retarding means, for said piston, within said retarding chamber and opening through said piston, a spring-pressed plunger suitably mounted in the casing and provided with a valve and a pusher, a valve for said seat and itself provided with a seat for the valve on said plunger, said second-mentioned valve having its seat located between said first-mentioned valve and said pusher, the arrangement of parts being such that a limited amount of movement independent of said second-mentioned valve is permitted to said first-mentioned valve and said pusher, and a hollow stem between said second-mentioned valve and said piston and opening through both.
